Patented July 1, 1919.

Attorney

UNITED STATES PATENT OFFICE.

AGNES D. KUNNEY, OF EARLVILLE, ILLINOIS.

FLY-GUARD.

1,308,597.

Specification of Letters Patent.

Patented July 1, 1919.

Application filed June 12, 1918. Serial No. 239,571.

To all whom it may concern:

Be it known that I, AGNES D. KUNNEY, a citizen of the United States, residing at Earlville, in the county of La Salle and State of Illinois, have invented certain new and useful Improvements in Fly-Guards, of which the following is a specification.

This invention relates to improvements in door attachments and it is the principal object of the invention to provide a novel fly guard which can be positioned adjacent a door and caused to operate upon the opening of the same in a manner to prevent flies and other insects from passing thereby through the door into the building.

Other objects will be in part obvious and in part pointed out hereinafter.

The improvements in the details and arrangement of parts will be apparent from an inspection of the accompanying drawings, in connection with the specific description hereinafter contained, and wherein is disclosed for the purpose of imparting a full understanding of the same.

In the drawings:

Figure 1 is a fragmentary side elevation of a screen door having the improved attachment arranged adjacent thereto,

Fig. 2 is a horizontal section therethrough, and

Fig. 3 is a fragmentary detail in perspective of a portion of the brush-carrying arm.

Having more particular reference to the drawings, in connection with which like reference characters will designate corresponding parts throughout the several views, 1 represents the screen door to which the improved attachment is applied, and 2 the frame receiving the same.

Bolted to one side of the door is a guard 4 serving to prevent injury to said door upon contact of the supporting plate 4' therewith which plate is hinged to the door frame 2, as at 3. Pivoted at one end to a portion of the support 4' is an arm 5, which as will be noted is offset as at 6 to space the free end thereof from the door 1 to permit free movement of the brush 7, carried thereby. An apertured arm 8 is connected to the arm 5 at a point adjacent its pivotal mounting, and has connection with one end of a contractile coil spring 9, which assists in supporting the arm in its normal horizontal position. The outer end of the spring is adjustably connected to the upper portion of

the support 4' through the medium of a bolt 10 passing through an eyelet 11 or similar device.

Pulleys indicated by the numeral 12 are mounted upon bearings secured to the support 4', and receive a flexible connection 13; one end of which is extended into engagement with a portion of the arm 5 as at 14, while the remaining end passes over a pulley 15 rotatably mounted on the outer portion of the screen door 1, downwardly into engagement with a rod 16, slidable in eyelets 17, also secured to the outer portion of the screen door. In this connection it is to be noted that the connection or cable 13 is maintained taut, while the arm 5 is maintained in its normal position by means of a contractile spring 5' engaged therewith and with the arm 5 by means of a weight 13' engaged with a portion thereof. The pull exerted upon the cable by the weight 13' assists the spring 9 in retaining the arm 5 in its normal horizontal position. A handle 18 is carried by the rod 16, and obviously affords means for facilitating the raising and lowering thereof, whereby the latch 19 can be moved out of engagement with the keeper 20, secured to the adjacent portion of the door frame and formed with an inclined bearing surface designated by the numeral 20'. In this connection, it is to be borne in mind that the latch 19 is of the usual spring pressed type and can be also operated by a knob 21 engaged therewith, for a purpose which will be subsequently apparent.

In operation, to open the door it is necessary to move the handle member 18 downwardly, thus causing the latch 19 to ride over the inclined bearing surface 20' of the keeper 20, and gradually disengaging the same therefrom. With the latch disengaged, the door is now free to be opened, and such movement thereof will cause the same to strike the hinged arm 4' moving the same outwardly with the door. As the handle member 18 is drawn downwardly the brush-carrying arm 5 will be swung upwardly to a vertical position, due to its connection with the cable 13, and in so doing the spring 9 is extended under tension and thus when the handle is released the arm is swung back to its horizontal position, arrested by the tension of the spring 9 and the pull exerted on the cable 13 by the weight 13', moving back and forth over the door will serve to prevent flies and other insects from passing thereby.

into the building through the doorway. It will be further understood, that the contractile spring 9 which assists in resiliently supporting the arm will serve to increase the vibratory or oscillatory motion of the brush-carrying arm subsequent to the starting of the same upon the abrupt pulling of the flexible connection 13. The tension of this spring may of course be varied by adjusting the bolt 10 to the desired degree.

Manifestly, the construction shown is capable of considerable modification, and such modification as is within the scope of my claims, I consider within the spirit of my invention.

I claim:

1. In combination with a hinged door, locking means therefor, a hinged support arranged adjacent the same and in the path of travel thereof, an arm pivoted to said support and extending therefrom, means connected to said arm for imparting oscillatory motion thereto upon operation of the locking means, and spring means engaged with said arm for prolonging the oscillatory motion.

2. In combination with a hinged door, a hinged support arranged adjacent the same and in the path of travel thereof, an arm pivoted to said support and extending therefrom, an apertured arm secured to said first

arm adjacent its pivotal mounting, a cable extending over the support into engagement with the first mentioned arm, and slideable latch means on the door having engagement with the remaining end of said cable.

3. In combination with a hinged door, a hinged support arranged adjacent the same and in the path of travel thereof, an arm pivoted to said support and extending therefrom, a brush carried on the free end of the arm, a cable extending over the support and connected to a portion of said arm, spring means engaged with the arm, and slideable latch means on the door having engagement with the remaining end of said cable.

4. In combination with a hinged door, an arm pivotally secured thereto, spring means normally retaining said arm in a predetermined position and operable to return said arm to its normal position subsequent to the movement of the arm upwardly to a vertical position, locking means for said door, and means connecting the locking means with the arm whereby the latter is actuated upon operation of the locking means and permitting independent movement of the arm with relation to the locking means.

In testimony whereof, I affix my signature hereto.

AGNES D. KUNNEY.
